US00D573552S

(12) **United States Design Patent**
Kim et al.

(10) **Patent No.:** US D573,552 S
(45) **Date of Patent:** ** Jul. 22, 2008

(54) **LIGHT EMITTING DIODE (LED)**

(75) Inventors: **Dae-Won Kim**, Seoul (KR); **Mi-Hae Kim**, Incheon-si (KR)

(73) Assignee: **Seoul Semiconductor Co., Ltd.**, Seoul (KR)

(**) Term: **14 Years**

(21) Appl. No.: **29/280,588**

(22) Filed: **May 31, 2007**

(30) **Foreign Application Priority Data**

Mar. 12, 2007 (KR) 30-2007-0010531

(51) **LOC (8) Cl.** 13-03

(52) **U.S. Cl.** D13/180

(58) **Field of Classification Search** D13/180; D26/2; 257/79, 80, 81, 88, 89, 95, 98, 99,

257/100; 313/483, 498, 500; 362/555, 800

See application file for complete search history.

(57) **CLAIM**

The ornamental design for light emitting diode (LED), as shown and described.

DESCRIPTION

FIG. 1 is a perspective view of an LED showing our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof; and,

FIG. 8 is a cross-sectional view taken along line VIII—VIII of FIG. 2.

1 Claim, 4 Drawing Sheets

FIG. 1

FIG. 2

FIG. 3

FIG. 4

FIG. 5

FIG. 6

FIG. 7

FIG. 8
